UNITED STATES PATENT OFFICE.

COLOMAN DE KANDÓ, OF BUDAPEST, AUSTRIA-HUNGARY, ASSIGNOR, BY MESNE ASSIGNMENTS, TO WESTINGHOUSE MACHINE COMPANY, A CORPORATION OF PENNSYLVANIA.

PRESSURE DEVICE FOR ELECTRIC-CURRENT COLLECTORS.

No. 875,788.

Specification of Letters Patent.

Patented Jan. 7, 1908.

Application filed May 6, 1905. Serial No. 259,246.

To all whom it may concern:

Be it known that I, COLOMAN DE KANDÓ, a subject of the King of Hungary, and a resident of Budapest, in the Empire of Austria-Hungary, have invented certain novel and useful Improvements in Pressure Devices for Electric-Current Collectors, of which the following is a specification.

My invention relates to means for maintaining the requisite pressure between a trolley and the trolley wire under different running conditions and it consists of certain novel parts and combinations of parts pointed out in the claims concluding this specification.

In the accompanying drawings, I have shown my invention applied in one of its simplest forms and it will be understood that various modifications may be made, and various detail forms of apparatus used, without departing from the spirit of my invention and without exceeding the scope of my claims.

In the accompanying drawings Figure 1 shows diagrammatically the complete arrangement at high speed running, with the trolley lifting device in a sectional elevation on a vertical plane. Fig. 2 is a horizontal section of the trolley lifting device on a larger scale, at low speed running. Fig. 3 shows the lifting pistons corresponding to the lowered position of the trolley pole. Fig. 4 is a view similar to Fig. 1 with means for connecting the motors in multiple. Figs. 5, 6 and 7 show a trolley lifting device adapted to afford three grades of pressure. Fig. 8 shows a trolley lifting device arranged so that the springs act normally to press the trolley with the maximum force against the trolley wire, the piston acting against the springs. Fig. 9 is a view substantially similar to Fig. 1 showing the trolley pole depressed.

The following is a description of the drawings, which show one form of structure embodying my present invention.

1 is one of the journals of the trolley pole 2 secured to the spindle 21, bearing on both ends arms 22. The lifting device comprises the cylinder 8 with a piston 3. The rod 7 of this piston bears the cross head 6. Springs 5 are connected respectively to said cross head and to the arms 22 of the trolley pole spindle.

A tube 13 provided with a flange 12 passes through the cover 23 of the cylinder 8 and projects into the cylinder. A piston 4 sliding with a central boring on the tube 13 is fitted in the cylinder 8, the stroke of said piston being limited at one end by the cover 23 and by the flange 12 at the other end. As the stroke of the piston 3 extends throughout the whole length of the cylinder 8, the rod 7 of said piston is provided with a recess 19 entered by the flange 12 when the piston 3 accomplishes its stroke from the position shown in Fig. 2 to that one shown in Fig. 3. To avoid the compression of the air in the recess 19 at this time an air escape 20 is provided in the flange 12.

24 and 27 are two three-phase induction motors. Two of the wires 25 leading to the primary windings of the motor 24 are connected with the trolleys, while the third wire 26 may be earthed.

18 is the speed controller, that is to say, a switch for connecting the motors 24 and 27 in cascade, or directly to the line. The speed controller comprises a plurality of stationary contact plates 29, 31, 33, 34 and a movable switch member 17, fitted with insulated contact brushes 36 and 37. The switch member is mounted on a piston 15 sliding in a cylinder 16.

The connections of the motors and the controller are the following: The secondary of the motor 24 is connected by the wires 28 to the contact plates 29 and the primary of the motor 27 is connected by the wires 32 to the contact plates 33. The secondary of the motor 27 is connected by wires 30 to the contact plates 31. The contact plates 34 are connected through the conductors 35 to a starting resistance 14 of any suitable kind.

The contact brushes 36 and 37, sliding on the stationary contact plates, establish in the lower position of the switch member 17, on one hand, the connection between the plates 29 and 33 and, on the other hand the connection between the plates 31 and 34. Hence, the secondary current of the motor 24 will flow through the wires 28, plates 29, brushes 36, plates 33 and wires 32 to the primary winding of the motor 27; and the secondary current of this motor 27 will flow through the wires 30, plates 31, brushes 37, plates 34, wires 35 to the starting rheostat.

14—that is to say, the motors will be connected to run in cascade. When, however, the switch member is elevated to the position shown in the drawing, the brushes 36 5 connect the plates 29 with the plates 34, and break the connection between the plates 31 and 34. The secondary current of the motor 24 flows, then, through the wires 28, plates 29, brushes 36, plates 34 and wires 35 directly 10 to the starting rheostat 14 and the motor 27 is cut out—that is to say, the car runs at full speed.

The switch member 17 of the controller 18 is operated by means of compressed air 15 stored in the reservoir 11. This reservoir is, through the pipe 38, in constant connection with the cylinder 16 above the piston 15, the tendency then being to press the switch member 17 in its lower position. A 20 pipe 39 and a branch 40 lead to the speed controlling valve 41. The pipe 42 connected to the casing of the valve 41 is branched, one branch 43 leading into the lower part of the cylinder 16 and the other branch, 44, leading 25 through the valve 45 and pipe 46 to the tube 13 of the trolley lifting cylinder. A pipe 9 connects, through the valve 10, cylinder 8 with the pipe 39. The valve 10 is adapted 30 to connect the pipe 9 either with the pipe 39, or through the outlet 47 with the atmosphere. The valve 10 may be operated by means of the handle 48 actuating a similar 35 valve between the pipes 44 and 46.

The valve 41 may be a suitable sliding 40 valve connecting, in the position shown in the drawing, the pipe 42 with the valve chamber 49 and shutting the outlet 50. This position corresponds to the high speed on single connection of the motor 24. If the handle 51 of the controlling valve is turned 45 in the opposite position, corresponding to the low speed or cascade connection of the motors, the pipe 42 is connected through the outlet 50 with the atmosphere.

50 When the trolley pole is lowered, (Fig. 9) on the one hand the valve 10 connects the pipe 9, and thus the cylinder chamber behind the piston 4, and on the other hand the valve 45 connects the pipe 46, and thus the 55 chamber between the pistons 3 and 4, with the atmosphere. At this time the controlling valve 41 is in the position connecting pipe 42, and thus the chamber under the piston 15 of the controller, through outlet 50 with the atmosphere.

To lift the trolley pole, the valve 10 is turned in the position connecting the pipe 9 with the pipe 39, and, hence, the chamber behind the piston 4 with the reservoir 11. 60 The compressed air entering the cylinder 8 between the piston 4 and the cover 23, will push the piston 4 outward until this latter abuts on the flange 12. Thereby the piston 4 will force the piston 3 into the position 65 shown in Fig. 2, stretching the springs 5 and

causing, by means of the arms 22 and the spindle 21, the trolley pole 2 to rise and the trolley to be pressed against the trolley wire with the pressure corresponding to the low speed of the car produced by the motors running in cascade connection. The motors may be now started by means of the rheostat 14. If hereafter it is desired to run the car with the high speed, the controller lever 51 is brought to the position shown in Fig. 1 75 of the drawings, whereby the valve 49 will put in communication the pipes 40 and 42. The compressed air will flow, on the one hand, through the pipe 43 into the lower chamber of the cylinder 16 and as the lower face of the piston 15 is larger than the upper face, the piston will be lifted, together with the switch member, into the position shown in Fig. 1 of the drawing, establishing the single or high speed running connection of the motor 24. 80 On the other hand, the compressed air will flow through the pipe 44, valve 45, pipe 46 and tube 13 into the space between the pistons 3 and 4 and will force the piston 3 to the position shown in Fig. 1; thereby increasing 85 the tension of the springs 5 and, therefore, the lifting pressure acting on the trolley pole 2. If the controlling valve is again turned in the position corresponding to the low speed, the lower chamber of the cylinder 16 90 is connected with the atmosphere and the switch member, dropping in its lower position, will connect the motors in cascade. At the same time the air escaping from the space 95 between the pistons 3 and 4 through the tube 100 13, pipes 46, 44 and 42 and the outlet 50, will allow the piston 3 to return in the position shown in Fig. 2, thus decreasing the tension 105 of the springs 5 and, therefore, the lifting pressure acting on the trolley pole to the amount required at low speed.

The arrangement shown and described is only an example, it being obvious that it may be varied without altering the scope of my invention. Thus, for example, the switch may be constructed so as to connect the motors 24 and 27 to the line in multiple for high speed running, instead of cutting out the motor 27, such direct connection of both motors to line under certain conditions possessing obvious advantages. This is illustrated in Fig. 4 where the parallel connection of motors is shown. If three induction motors are provided which may be run in triple cascade, cascade and direct (either single or multiple) and thus three grades of speed be produced, the pressure acting on the trolley lifting device may be increased correspondingly in three steps. This is shown in Figs. 5, 6 and 7. Fig. 7 shows the position of the device when the pole is in the position of minimum pressure or lowered. Air admitted by pipe 9 puts the parts in the positions indicated in Fig. 6. Thereafter air admitted by pipe 13^b puts the parts in the positions in- 120 125 130

dicated in Fig. 5. Thereafter air admitted by pipe 13^a extends the parts to their limit as will be readily understood. If direct current motors are used or induction motors with speed regulating resistances, the speed of which can be varied gradually, the motor controller may operate simultaneously an air pressure controller of any suitable kind, varying the pressure acting on the lifting device of the trolley according to the speed of the motor, corresponding to the position of the motor controller. Further, the lifting device may be arranged in such a manner that the springs act normally to press the trolley with the maximum pressure on the trolley wire and the pistons may act against the springs, diminishing the pressure of the springs with the increasing air pressure. In this case the pressure of the compressed air should, of course, diminish, when the speed of the car grows. This is illustrated in Fig. 8 where the extension of the cylinders operates to diminish the force of the springs, as will be readily understood.

25 Certain features of invention described but not claimed herein are the subject of my co-pending application filed November 27, 1903, Serial No. 182,701.

Having thus described one embodiment of my invention, what I claim and desire to secure by Letters Patent is:

1. The combination with an electric vehicle, of an electric conductor, an electric current collector, a plurality of electric motors for propelling said vehicle, a controller for arranging the connections of said motors for running-speeds of different orders, and means for pressing the collector toward the conductor with relatively low pressure when the motor connections are arranged for a running speed of relatively low order, and for pressing the collector toward the conductor with relatively high pressure when the motor connections are arranged for a running-speed of relatively high order.

2. The combination with an electric vehicle, of an electric conductor, an electric current collector, a plurality of induction motors for propelling said vehicle, a controller for arranging the connections of said motors in single and in cascade, and means for automatically pressing the collector toward the conductor with a relatively low pressure when the motors are arranged in cascade, and for pressing the collector toward the conductor with relatively high pressure when the motors are connected in single.

3. The combination with an electric vehicle, of an electric conductor, a current collector, a plurality of motors and fluid-operated means for arranging said motors to vary the speed of the vehicle and for simultaneously varying the pressure of the collector toward the conductor.

4. The combination with an electric vehicle- 65 of an electric conductor, a current collector, a plurality of motors and unitary means independent of the current flowing to the motors for arranging said motors to vary the speed of the vehicle and for simultaneously varying the pressure of the collector toward the conductor.

5. The combination with an electric vehicle- 75 of an electric conductor, a current collector, a plurality of motors, a controller, fluid-operated means controlled by said controller for arranging said motors to vary the speed of the vehicle and fluid-operated means simultaneously controlled by said controller for varying the pressure of said collector to- 80 ward said conductor.

6. The combination with an electric vehicle- 85 of an electric conductor, an electric current collector, a plurality of induction motors, a starting device for said motors, switch mechanism for said motors, means for automatically actuating said switch to connect said motors directly and in cascade, such means also operating to press the collector against the conductor with relatively great force 90 when a motor is running singly and with less force when the motors are running in cascade.

7. The combination with an electric vehicle- 95 of a motor, an electric conductor, an electric current collector, a starting device for 100 said motor, a supply of compressed fluid, a switch mechanism for said motor, means for exerting fluid pressure upon the switch to operate the latter, and means for simultaneously applying fluid pressure to the collector 105 to maintain the latter in contact with said conductor when the vehicle is at rest, and means connected with said starter for automatically increasing the force exerted to press said collector against said conductor 110 when the vehicle is in motion.

8. The combination with an electric vehicle- 115 of a plurality of motors, a starting device for said motors, an electric conductor, an electric current collector, switch mechanism for connecting said motors directly or in cascade, a compressed fluid supply, means for conducting the fluid to the switch to operate the latter, a piston and piston chamber mounted adjacent to the current collector, a connection between said piston and the collector, means for conducting a supply of fluid to the piston chamber to operate the piston therein and press the collector against the conductor, and a controller for regulating the admission 120 of air to the switch and to the piston chamber.

In witness whereof I have signed my name to this specification in the presence of two subscribing witnesses.

COLOMAN DE KANDO.
